UNITED STATES PATENT OFFICE.

ROBERT KLOTZ, OF CHICAGO, ILLINOIS.

ADVERTISING DEVICE.

1,004,660.

Specification of Letters Patent.

Patented Oct. 3, 1911.

Application filed April 8, 1907. Serial No. 366,952.

To all whom it may concern:

Be it known that I, ROBERT KLOTZ, a citizen of the United States, residing at Chicago, in the county of Cook and State of Illinois, have invented a new and useful Improvement in Advertising Devices, of which the following is a complete specification.

This invention relates to improvements in advertising devices and has for its object the 10 production of a device of such unique design as to attract the attention of all, and also to provide a device suitable for use as a desk fixture, such as a combined stamp or label holder and ink well, and which acts 15 when the stamp receptacle is opened, to present a damped surface on which to moisten the stamps.

It is also an object of the invention to provide a device embodying the bust of any 20 person whom it is desired to bring prominently before the public, as for instance political personages, or persons whose names are associated with articles of manufacture or commerce.

25 The invention consists of the matters hereinafter described in the specification and more fully pointed out and defined in the appended claims.

In the drawings: Figure 1 is a front elevation of a device embodying my invention. Fig. 2 is a section taken on line 2—2 of 30 Fig. 1.

As shown in said drawings: The device embodies the general outline of the bust of 35 the individual to be represented and comprises a casing 1 of any preferred construction and material, and on which the head 2 is mounted. Said casing may be of any desired shape, and, as shown, it is provided at 40 each end thereof with a receptacle 1' for ink or other material and which opens at the top and is closed by a hinged lid 1². Said receptacles are adapted to contain ink or other material usually used about a desk.

45 The lower jaw 3 is pivoted in the rear portion of the head on pins 3' and the forward end thereof, or the chin, is adapted to drop down within the collar 4 when the mouth is opened. A shaft 5 is journaled in 50 the side walls of the casing adjacent the lower rear corners thereof, and a rod or arm 6 is rigidly engaged on said shaft and extends upwardly into the head. Carried on the upper end of said arm 6 is the tongue comprising a plate 7 on which is carried, as shown, a sponge, or other absorbent material 8,

adapted to contain moisture. A forked lever 9 is rigidly engaged at one end to the shaft 5 and normally extends upwardly and forwardly therefrom at an angle of approximately 45 degrees, as shown in full lines in Fig. 2. Near its forward end said lever is pivoted to the lower end of the link 9', the upper end of which is pivoted to the forward end of the jaw 3. The weight of the jaw is such that it tends to force the link 9' and consequently the forward end of the lever 9 downwardly, thereby projecting the tongue from the mouth, as shown in dotted lines in Fig. 2.

The casing is open at its front and a drawer 10 is slidably engaged therein and is provided with a downwardly inclined rear wall 10' adapted to slide beneath the lever 9, which has a roller 9² journaled on the front end thereof and is adapted to travel on said inclined wall. At the top of said inclined wall is a flat ledge 10² on which the roller rests when the drawer is closed.

A flanged receptacle 11 is provided in the 80 crown of the hat 12, and a cover 11' fits over the crown and closes said receptacle. Connected to the bottom of said receptacle is a pipe 13 which opens into one side of the valve casing 13' supported by said pipe 85 above the base of the tongue. On the opposite side of said casing from the pipe 13 is a pipe 13², which opens from the casing and extends forwardly and downwardly to near the mouth. A valve closure 13³ is rotatively 90 engaged in said valve casing and is provided with an aperture therethrough which, when the closure is in one position, is in register with the pipes 13 and 13² and permits water from the receptacle to flow therethrough 95 onto the tongue. Said closure is provided at one end of the valve casing with a pair of arms 14 and 14', the former of which is directed downwardly and forwardly, and the latter of which is directed downwardly 100 and rearwardly and are adapted to contact respectively with lugs 15 and 15' on the rear end of the tongue which act to operate the valve.

The operation is as follows: The receptacle 11 is filled with water and the drawer 10 may contain postage stamps or the like and when the drawer is opened, as shown in dotted lines in Fig. 2, the forward end of the jaw is permitted to drop as the inclined wall of the drawer is withdrawn from beneath the front end of the lever 9. As the

tongue moves forwardly the lug 15 contacts with the arm 14 and turns the valve closure to open position, thereby permitting water to flow from the receptacle to the sponge on 5 the tongue and wet the same. As the drawer is closed the incline is forced beneath the front end of the lever 9 thereby raising the jaw and drawing the tongue inwardly, and, as it moves inwardly, causes the lug 15' to 10 engage the arm 14' and close the valve.

While I have shown the device as embodied in a stamp or label holder, it obviously is as well adapted for use as a match holder, in which case, the tongue may be 15 provided with a roughened surface on which to ignite the matches. Obviously also many details of form and construction may be varied without departing from the principles of my invention.

20 I claim as my invention:

1. The combination with a head having a jaw pivoted therein, of a tongue supported in the head by means adapted to permit its protrusion, and a drawer normally in engagement with said means and adapted by 25 disengagement therefrom to permit the jaw to open and the tongue to project simultaneously.

2. In a device of the class described the 30 combination with a pivoted jaw, of a tongue reciprocatably supported above the same, a sliding drawer and means operated by the movement of said drawer adapted to operate the tongue and jaw.

35 3. In a device of the class described the combination with a casing of a head mounted thereon, a shaft journaled in said casing, a reciprocative tongue carried on said shaft, a jaw pivoted in the head, a lever rigidly 40 engaged on said shaft, operative connections between said lever and jaw and means slidably engaged in said casing adapted to operate the jaw and tongue.

4. In a device of the class described the 45 combination with a head, of a casing beneath the same, a reciprocating tongue in said head, a jaw pivoted in the head, operative connections between the tongue and jaw and means adapted to simultaneously open 50 the jaw and protrude the tongue, and close the jaw and retract the tongue.

5. In a device of the class described the 55 combination with a hollow member, of a jaw pivoted therein, a shaft journaled in said member, an arm rigidly engaged on said shaft, a tongue mounted on said arm, a lever rigidly engaged to said shaft, a link connecting said lever and jaw and means slidably engaged beneath the lever adapted to 60 simultaneously operate the jaw and tongue.

6. In a device of the class described the 65 combination with a casing, of a head thereon, a jaw pivoted in said head, a reciprocative tongue, means operatively connecting the jaw and tongue, actuating means therefor

and means adapted to moisten the tongue when the tongue is operated.

7. In a device of the class described the combination with a casing, of a head thereon, a jaw pivoted in said head, a tongue reciprocatably supported above the jaw, means connecting said jaw and tongue, a drawer engaging said means and adapted when moved to operate the jaw and tongue, a receptacle above the tongue, a pipe connected 70 therein and extending forwardly and downwardly to the tongue and a valve in said pipe adapted to be operated by the movement of the tongue.

8. In a device of the class described the 80 combination with a casing of a hollow head thereon, a jaw pivoted in said head, a shaft journaled in the casing, an arm thereon, a plate on said arm, absorbent material on said plate, a lever rigidly engaged on said 85 shaft, a link connecting said lever and jaw, a roller on the end of said lever, a drawer slidably engaged in the casing and having an inclined end thereon adapted to engage said roller and operate the lever, a receptacle in the top of the head, a pipe connected therewith, a valve in said pipe and means adapted to operate the valve and supply 90 water from the receptacle to said absorbent material.

9. In a device of the class described the combination with a casing of a head thereon, a drawer slidably engaged in said casing, a jaw pivoted in the head, a tongue reciprocatably supported above the jaw, means 100 connecting said jaw and tongue and adapted to operate the same when the drawer is moved and means operated by the movement of the tongue adapted to supply moisture thereto.

10. In a device of the class described the combination with a head of a tongue supported therein, means adapted to protrude said tongue, and means operated by the movement of the tongue adapted to supply 110 moisture thereto.

11. In a device of the class described the combination with a head of an absorbent tongue therein, a source of liquid supply above said tongue, a valve controlling the 115 same, means adapted to protrude the tongue, and means adapted to operate the valve and supply liquid to the tongue when the latter is protruded.

12. In a device of the class described the 120 combination with a head of a jaw pivoted therein, a tongue above said jaw, means adapted to simultaneously open the jaw and protrude the tongue, and means operated by the movement of the tongue and adapted to 125 deliver moisture thereto.

13. In a device of the class described the combination with a head of a jaw pivoted therein, a tongue supported above said jaw, a receptacle in the top of the head, a tube 130

leading downwardly therefrom to a point above the tongue, a valve in said tube, means adapted to simultaneously open the jaw and protrude the tongue, and means on the 5 tongue adapted to operate said valve.

14. The combination with a head, of a reciprocating tongue therein, means adapted to reciprocate the tongue, a fluid receptacle above the tongue, an outlet pipe leading 10 from the receptacle to a point above the tongue, a valve in said pipe, and coacting

means on the valve and tongue adapted to operate the valve when the tongue is reciprocated.

In testimony whereof I have signed my 15 name to this specification in the presence of two subscribing witnesses.

ROBERT KLOTZ.
